UNITED STATES PATENT OFFICE.

FREDERIC PAYSON REED, OF EAST ORANGE, NEW JERSEY, ASSIGNOR, BY MESNE ASSIGNMENTS, TO CHARLES C. ORCUTT.

PAPER-DRYING APPARATUS.

Application filed February 6, 1920. Serial No. 356,669.

To all whom it may concern:

Be it known that I, FREDERIC PAYSON REED, a citizen of the United States, residing at No. 234 N. Grove Street, East Orange, 5 in the county of Essex, State of New Jersey, have invented certain new and useful Improvements in Paper-Drying Apparatus; and I do hereby declare the following to be a full, clear, and exact description 10 of the invention, such as will enable others skilled in the art to which it appertains to make and use the same.

The present invention is a quick drying apparatus to be utilized in connection with 15 a Fourdrinier machine, or other paper making apparatus, and is intended to supplant the bulky and expensive drying rolls now utilized with such machines. By reason of the intense heat applied, and the directness 20 of its application, the necessary drying can be accomplished quickly and efficiently.

It is well known that in ordinary paper making machines, the paper passes from a 25 series of press rolls to a drying apparatus which consists of a large number of steam-heated cylinders, sometimes thirty or more, carrying a felt belt or apron. The paper, in such machines, is thus separated from 30 the source of heat by a solid damp belt through which, by conduction, the heat passes to the paper.

According to the present invention, the paper is carried on a metal screen, or the 35 like, and receives its heat more directly and more effectively.

The drier of the present invention may be constructed in the form of a table with a 40 traveling screen top, but other suitable means for carrying the paper may be utilized whereby it is passed over a source of heat, directly applied. Whatever the form of machine used, dry air of high temperature is applied directly to the surface of the 45 traveling paper.

An advantage of the apparatus embodying this invention is that the paper, in traveling over the drier, is not subjected to undue stresses such as may arise from 50 changes in the usual hot, moist carrying apron or felt. Likewise, there are no smooth, highly heated surfaces to which the paper might adhere.

Another advantage incident to the use of

a screen is that a temperature is possible 55 which would quickly scorch ordinary dryer felts. By utilizing a metal screen and direct heating, the heat losses are reduced to a minimum and a high paper speed is permissible.

Another advantage of using a screen having ample air spaces, with heat passing therethrough, is that the highly heated air of the room is circulated and passed upwardly to the under side of the paper. The 60 currents of air also substantially surround all the metal used, so that there is no sticking incident to highly heated material coming in contact with the soft, pulpy, moist 65 surface of the paper.

Another advantage incident to the use of a metal web or belt is the absence of local shrinkage or change in form of the belt. Still another important advantage is that by the use of the screen belt it is not necessary, at the time of any stoppage of the 70 machine, to lift the paper from the belt, provided the heat is to be cut off, for by reason of the air spaces, air currents quickly carry the scorching heated air out of contact with the paper, and at the same time, cooler, unheated air is drawn in underneath the paper. Also, at the time that the paper is stopped, no attention is required in connection with condensed steam, always present 75 in the case of steam-heated rolls, and there is no excessive steam in the drying section of the mill. It has been found that the moisture driven from the paper offsets the drying action of the heater, and a substantially 80 normal atmosphere is maintained.

The foregoing advantages, and others, will be manifest from the following description of the drawings forming a part of this specification, wherein—

Figure 1 is an elevational view of a portion of the device introduced after the press rolls and drying cylinders of a Fourdrinier machine;

Fig. 2 shows the remaining portion of the 100 device of Fig. 1, and, taken with Fig. 1, shows two of the drying tables, and a plurality of drying cylinders equipped in a manner similar to the drying tables;

Fig. 3 shows in detail a single table 105 equipped with a wire screen belt;

Fig. 4 shows in detail a single drying table having a modified form of belt;

Fig. 5 shows a top plan view of a drying table with paper in position upon the screen belt and its supports;

Fig. 6 shows the screen of the invention applied to a drying cylinder; and

Fig. 7 shows a section of a cylinder with the screen in detail, and a source of heat within the cylinder.

The last press of the Fourdrinier, or like machine, represented at the left of Fig. 1, delivers the paper 1 to one or more drying cylinders 2, which pass the paper to one or more of the drying tables which may be duplicated at will. The table or bench 3 carries upon its top 4 at each end thereof frame members 5 supporting thereupon guide rolls 6 which may be power driven for carrying and driving the screen belt or apron 7.

20 The screen belt, later to be described in detail, moves over and across a series of hot plates 8 which are mounted transversely on the table, and suitably supported at the ends of the table upon the frame member 5. They 25 are mounted at their edges intermediate the ends of the table upon frame members 9. Beneath the several hot plates thus provided are transverse burners 10, which in one form comprise gas pipes having staggered outlets 30 therein. The outlets are provided with the usual individual gas burners whereby a uniform flame is applied to the under surface of the hot plates 8. The burners may, of course, be replaced by resistance wires forming electric heaters, or by any other direct heating source applicable to this invention.

The length of the drying table is not limited, although there is shown upon the top thereof three frames 9 with rolls 11 carrying the screen belt 7. The upper surface of these rolls contacts with the screen belt 7 and serves to support said belt and the paper carried thereupon.

When the paper has crossed one of these 45 drying tables, it leaves the screen belt 7 and passes to another portion of the machine. Belt 7 passes downwardly around tension pulley 16 and guide roller 17 as shown.

Beyond the drying tables are cylinders 18, 50 19 and 20 which have screens secured upon their outer surfaces. The cylinders 18, 19 and 20 are heated upon their interiors, the heating apparatus in this case, for illustration only, being shown as a gas burner 21 55 which is duplicated transversely of the cylinder as practice may dictate. Other sources of heat may be used in place of the gas burners shown.

While in Fig. 2 the surface of the drying 60 table is shown as straight and horizontal, the hot plates may be disposed in the form of a gentle slope to the center of the table, and from the center downwardly to the other end as shown in Fig. 3. The convexity may 65 be greater than that shown in Fig. 3.

The screen belt forming part of this invention comprises a wire netting (Fig. 5) of woven or interlaced members (Fig. 7) of any suitable cross section, and of moisture and corrosion resisting material not distorted by heat, having air spaces as large as possible consistent with a firmly made mesh, screen, net, or similar formation. That is to say, the wires or corresponding parts, may be reduced to the minimum in cross section, 75 and made infrequent, or they may be made as large and frequent as practice may dictate, it being obvious that the net should be made of an endless form with no tendency to distort in the direction of its length or 80 breadth. As shown in Figs. 1, 2 and 5, it comprises a single web of netting of somewhat greater width than the paper to be handled, and either maintained by tension rolls in the taut condition, or stretched upon 85 cylinders in a neat close-fitting manner by proper fastening means, as shown in Figs. 6 and 7. Perforated members, such as are formed by punching sheets can be used.

A modification of the foregoing construction of screen belt, hot plates and table will be seen in Fig. 4, where the screen belt is mounted upon, and properly fastened to, a thin flexible metal belt 12 maintained under tension. Care should be taken to have the 90 materials of the screen and the thin metal belt of the same co-efficient of expansion, so that there shall be no puckering of the screen above the belt.

This double belt travels across the table in 100 a manner similar to that already described, although it will be noted that the intermediate frames 9 are modified in Fig. 4. By using the thin metal belt 12, the hot plates 8, shown in Figs. 1, 2 and 3, are done away 105 with so that the heat sources 10 are uniformly distributed and spaced with the guide rolls 11 on the top of the table. In this manner well distributed heat is applied to the drying belt throughout its travel 110 across the table.

Although the drawings do not show it, the paper is carried from the drying tables and cylinders to a winding roll, well-known in the art and properly omitted from the 115 drawings of this application.

The terms "mesh", "netting" and "screen", used herein, are intended to refer to and include all construction of similar formation capable of performing the functions herein 120 described, whether they be foraminous, perforate or of like formation, and of metal or any other material, in the form of wire or the like.

It is not intended to limit the foregoing 125 invention to the drying of paper in its manufacture, for it is obvious that the invention may be advantageously used in the drying of wall paper and many other materials and manufactured articles.

While the preferred embodiment of the invention has been described hereinabove, and illustrated in the drawings, no limitation to the precise structure comprised in such disclosure is contemplated, excepting in so far as may necessarily be imposed by the language of the appended claims, since the invention is thoroughly susceptible of considerable modification and change within the scope of said claims, and since parts of the invention as disclosed may be employed without others, and in other and different environments.

I claim:

- 15 1. In a drying apparatus, a source of heat, a substantially horizontal plate heated thereby, a screen belt in close proximity to said plate and adapted to carry the material to be dried, and supporting and driving means for said belt, said screen belt enclosing a layer of air above the hot plate, heated thereby, and passed to the surface of the material to be dried.
- 20 2. In an apparatus for drying material, an imperforate stationary surface over which the material is passed, means to heat said surface, and a perforate member in close

proximity to said imperforate surface for supporting the material, means for moving said perforate member over the imperforate 30 surface, said perforate member serving to space the material from the heated imperforate surface and serving to confine between the material and the heated imperforate surface a relatively large layer of air.

35

3. In an apparatus for drying material a source of heat, a surface distributing said heat, a paper carrying member traveling across said heating surface in close proximity thereto and having passages through 40 which heated air may travel and impinge directly upon the paper.

4. In an apparatus for drying material, a substantially horizontal heated surface, and means between said surface and the material 45 for supporting the material, said means contacting with the material and with the surface over relatively close set restricted areas, and the said means being perforate to permit the free circulation of air between the 50 material and the said surface.

In testimony whereof I affix my signature.

FREDERIC PAYSON REED.
